UNITED STATES PATENT OFFICE.

ERNEST T. HEINSON, OF MOUNTAIN IRON, MINNESOTA.

OPEN-AIR SLEEPING ROOM.

Application filed December 31, 1925. Serial No. 78,616.

This invention aims to provide a novel means whereby the occupants of different compartments in a sleeping porch may obtain privacy and protect themselves against undesirable weather conditions, it being possible to maintain all of the advantages of an open air sleeping porch. Although the device may be used advantageously in connection with sleeping porches, it is not confined to that use, but may be employed wherever desired.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a device of the class described constructed for use on an inside partition between rooms in a sleeping porch, in a building, or elsewhere;

Figure 2 is a section on the line 2—2 of Figure 1;

Figure 3 is a section on the line 3—3 of Figure 2;

Figure 4 is an elevation showing that form which is used on the outside wall of a building, sleeping porch or the like;

Figure 5 is a section on the line 5—5 of Figure 4;

Figure 6 is a section on the line 6—6 of Figure 4;

Figure 7 is a perspective view showing a portion of one of the pressure members.

In Figures 1, 2 and 3, the numeral 1 marks a partition in a building, sleeping porch or the like. In the partition 1 is mounted a frame 2 which may include a hollow lintel 3, pairs of stiles 4, and a sill 5. The lower portion of the frame 2 is closed by an opaque panel 6. The panel 6 extends between the pairs of stiles 4 and rests on the sill 5. A frame 7 extends between the panel 6 and the lintel 3. The frame 7 extends between the stiles 4 of the pairs, as shown in Figure 3. The frame 7 carries a

screen 8. The stiles 4 are provided with flanges 9. Opaque solid closures 10 slide between the flanges 9 and the panel 6. The closures 10 are of such size that when they are drawn up and slid inwardly, they may be lodged within the screen frame 7. Eyes 11 or the like are connected to the upper edges of the closure 10. When the closures are raised and slid inwardly into the screen frame 7, the eyes 11 are received in recesses 12 that are formed in the upper rail of the screen frame 7. Flexible elements 14 are connected to the eyes 11 on the closures 10 and are rove over sheaves 15 on the lintel 3. Brackets 16 are mounted on the stiles 4 and are located near the upper edge of the panel 6. Spring actuated rollers 17 are journaled in the brackets 16. Curtains 18 are wound about the rollers. Flexible elements 19 are connected to the curtains. Flexible elements 19 are rove over sheaves 20 on the lintel 3. The flexible elements 14 and 19 are belayed on cleats 21 on the stiles 4, or held in any other desired way.

If an occupant of a room on either side of the partition 1 requires a moderate degree of privacy, he can haul up his curtain 18 and make the line 19 fast to one of the cleats 21. If he desires that privacy which is afforded by a solid partition, he can haul up the closure 10, push the closure into the screen frame 7, where it is held frictionally, and dispose of the line 14 as he considers best, for instance, by hanging it on one of the cleats 21. It is possible, of course, to lower both curtains 18 and to drop both closures 10, whereupon the screen 8 remains open and uncovered, and free circulation between the adjoining rooms of a sleeping porch or other structure is afforded.

In Figures 4, 5, 6 and 7 of the drawings there is shown a device which is adapted to be used on the outer wall of a sleeping porch, to secure privacy, protection from the weather, and the like, without impairing the utility of the building as an open air sleeping porch; and although a sleeping porch has been mentioned, the structure herein-after described may be used elsewhere than on a sleeping porch.

The numeral 22 marks an outer wall in which is mounted any desired number of frames 23 each including a hollow lintel 24 stiles 25 and a sill 26. Plates 27 are seated in the stiles 25 and are held therein by securing elements 28, such as screws. The

plates 27 have ribs 29, 30 and 31 which project inwardly. The ribs 31 are wider than the ribs 29 and 30. An upper screen frame 32 slides between the ribs 29 and 30, the screen in the frame being marked by the numeral 33. The lower screen frame 34 slides between the ribs 30 and 31, and the screen of that frame is marked by the numeral 35. A spring-actuated roller 36 is journaled in the hollow lintel 24. About the roller 36 is wound a curtain 37 of flexible transparent material. The curtain 37 extends downwardly through a slot in the bottom of the lintel 24 and slides in contact with the rib or flange 31 on the plate 27. A spring-actuated roller 38 is journaled in the hollow lintel 24. The roller 38 carries a flexible curtain 39. The curtain 39 is made out of material which is rain-proof and sun-proof. The curtain 39 extends downwardly through a slot in the bottom of the lintel 24 and slides in contact with flanges 40 on the plates 27. A means is provided for holding the curtain 37 against the ribs 31, and for holding the curtain 39 against the flanges 40. This means may be in the form of wings 41 having inwardly extended lips 42 adapted to bear on the curtains, the lips being pivotally mounted on rods 43 carried by bracket plates 44, springs 45 being engaged about the rods and cooperating with the bracket plates 44 and with the wings 41 to urge the wings against the curtains 37 and 39, thereby preventing the curtains from flapping about, without interfering with the sliding movement of the curtains. The bracket plate 44 for the device that cooperates with the curtain 37, is mounted on the plate 27, as shown in Figure 6, whereas the bracket plate 44 of the device which cooperates with the curtain 39, is mounted on the stile 25.

Brackets 46 are mounted on the stiles 25 near the sill 26, and in the brackets 46, a spring-actuated roller 47 is journaled, the roller carrying an upwardly extended curtain 48, which may be made out of common and usual window curtain fabric, the curtain 48 being connected to flexible element 49 extended over a pulley 50 on the lintel 3 and downwardly to a cleat 51 on the stile 25.

It is clear that the operator may lower the curtain 48, and raise the curtains 37 and 39, whereupon the screens 33 and 35 will be fully

exposed, to permit a circulation of air. The operator may pull up the curtain 48 as much as he desires. If he wishes to provide a substantially wind-tight closure, and still have light, he pulls down the flexible transparent curtain 37, and if he wishes protection against the elements, the curtain 39 is lowered.

What is claimed is:—

1. In a device of the class described, the combination of a main frame, an opaque panel in the lower part of said frame, a screen frame in the upper part of said main frame and resting upon said opaque panel, sliding solid closures mounted at opposite sides of said opaque panel and adapted to fit into opposite sides of said screen frame for closing the same, and manually operated means connected to said solid closures for raising the same to a parallel position with said screen frame prior to said closures being forced into said screen frame.

2. In a device of the class described, the combination with a main frame, of an opaque panel in the lower part of said main frame, a screen frame in the upper part of said main frame and resting upon the upper edge of said opaque panel, solid closures slidably mounted in said main frame and normally positioned at opposite sides of said opaque panel, said solid closures provided with eyes on their upper edges, said screen frame provided with a pair of recesses in its upper portion for receiving said eyes, said solid closures adapted to both fit into said screen frame with said eyes in said recesses, and manually operated means connected to said eyes for raising the solid closures in said main frame to a parallel position with said screen frame prior to said closures being forced into said screen frame.

3. In a device of the class described, the combination with a main frame, of a screen frame and an opaque panel positioned one above the other and in the center of said main frame, sliding closures at opposite sides of said opaque panel and of less size than said screen frame, and said sliding closures being adapted to rest snugly within the screen frame when raised parallel therewith and pushed into said screen frame.

In testimony that I claim the foregoing as my own, I have hereto affixed my signature.

ERNEST T. HEINSON.
